UNITED STATES PATENT OFFICE.

HOWARD M. BARBER, OF STONINGTON, CONNECTICUT, ASSIGNOR, BY MESNE ASSIGNMENTS, TO C. B. COTTRELL & SONS COMPANY, OF NEW YORK, N. Y., A CORPORATION OF DELAWARE.

SHEET CUTTING AND FEEDING MECHANISM FOR PRINTING-PRESSES.

1,205,840.

Specification of Letters Patent.

Patented Nov. 21, 1916.

Application filed December 13, 1913. Serial No. 806,531.

To all whom it may concern:

Be it known that I, HOWARD M. BARBER, a citizen of the United States, and resident of Stonington, in the county of New London 5 and State of Connecticut, have invented a new and useful Improvement in Sheet Cutting and Feeding Mechanism for Printing-Presses, of which the following is a specification.

10 The object of this invention is to provide means for cutting sheets of different lengths from a continuously moving web and to feed the sheets thus cut in register to the printing mechanism.

15 This invention comprises means for varying the speed of the web according to the length of sheets to be cut therefrom.

It also includes coacting cutters rotating at a variable speed so that at the moment of 20 cut the cutting knives will travel at the speed of the web.

It also includes adjustable means for feeding the sheets from the cutters to the printing mechanism.

25 My invention more specifically includes a group of web feed rolls arranged to be driven at different speeds so as to deliver the proper amount of web, for any desired length of sheet, to the rotary cutters.

30 It also more specifically includes a sheet feeding means interposed between the rotary cutters and the printing mechanism, which means comprises three rotary sheet carriers, the first carrier being adjustable toward and 35 away from the rotary cutters and the second carrier being adjustable in a curve and concentric to the axis of the third rotary carrier, so that the three rotary carriers are kept in coactive relationship to each other 40 and with respect to the cutters and the printing mechanism.

A practical embodiment of my invention is represented in the accompanying drawings, in which—

45 Figure 1 represents in side elevation so much of a rotary sheet feed printing press as will give a clear understanding of the invention, Fig. 2 is a diagrammatic section showing the parts in the positions which they 50 assume when a long sheet is being cut and fed to the printing mechanism, Fig. 3 is a

similar view showing the parts in the positions which they assume when a shorter sheet is being cut and fed to the printing mechanism, Fig. 4 is a detail section on an 55 enlarged scale through the sheet feed rolls, Fig. 5 is a detail section showing the arrangement of the train of gears for feeding the proper length of web for the long sheet, and Fig. 6 is a similar section showing the 60 train of gears for feeding the proper length of web for the shorter sheet.

The printing mechanism illustrated herein comprises an impression cylinder 1 and its plate cylinders 2, 3, 4 and 5.

65 The means illustrated herein for delivering the sheets from the impression cylinder 1 comprises the transfer cylinders 6, 7, and the delivery cylinder 8 arranged to deposit the printed sheets in a pile on the table 9.

70 It is understood that the printing mechanism and delivery mechanism may be of any well known or approved construction and forms no part of the present invention.

75 The coacting rotary cutters are denoted by 10, 11, and their blades by 12, 13. These cutters are provided with intermeshing gears 14, 15, as is usual. These cutters make one revolution for each sheet cut from the web and they are driven through a pair of 80 elliptical gears 16, 17, from the shaft 18 at a variable speed so that the blades 12 and 13 may be caused to travel at the speed of the web during the cutting operation.

85 The web is denoted by 19 and the means for feeding the web to the rotary cutters is shown herein as comprising four rolls 20, 21, 22, 23. Gears 24, 25, 26, 27, form a driving connection between said rolls. The shaft 28 of the roll 22 is provided with a gear 90 29, which gear is driven from the gear 30 on the shaft 18 through the gears 31, 32, mounted on the idler shaft 33, which shaft is movable in a curved path concentric with the shaft 18. The surface speed of the rolls 95 20, 21, 22, 23, may be varied by introducing a larger or smaller gear 32. For instance, where a long sheet is to be cut and fed to the printing mechanism, the web is fed more rapidly by the introduction of a large gear 100 32, as shown in Fig. 5, and where a shorter sheet is to be cut and fed the web is driven

at a slower speed by introducing a smaller gear 32. It is evident that the speed of the web can, by this means, be accurately adjusted to feed the desired amount for any desired length of sheet.

Sheet feed rolls 34, 35, are located below the rotary cutters 10, 11, and are geared together through the gears 36, 37. The feed roll 35 is provided with a slip clutch connection 38 between it and its shaft 39 so that the tail end of a sheet may be drawn from between the two rolls at a greater speed than the speed of the rolls when so desired as will hereinafter more fully appear.

10 The shaft 39 of the feed roll 35 is driven from the shaft 40 of the web feed roll 23 through the bevel gears 41, 42, vertical shaft 43, and worm and gear 44, 45. Guides 46, 47, serve to guide the web from the rotary cutters 10, 11 to the feed rolls 34, 35. The shaft 18 is driven from the impression cylinder gear 48 through the train of gears 49, 50, 51, 52, 53.

15 The adjustable means for feeding sheets of different lengths to the printing mechanism comprises three coacting rotary carriers, in the present instance reels 54, 55, 56, which are driven at the proper speed from the impression cylinder gear 48 through the gears 57, 58, 59. The shaft 60 of the third reel 54 is mounted in fixed bearings in the machine frame. The shaft 61 of the second reel 55 is mounted to move in a curved path concentric with the shaft 60 20 of the third reel 54. The shaft 62 of the first reel 56 is mounted in suitable bearings in the sliding carriages 63 at both sides of the machine.

25 The first reel 56 is movable in a right line toward and away from the feed rolls 34, 35, by means of a screw shaft 64, which engages a traveling nut 65 on each of the carriages 63. Each of these screw shafts is mounted in upper and lower bearings 66, 67, and is rotated through a worm and gear connection 68, 69, from a cross shaft 70 having a suitable operating handle 71 at one side of the machine. Tucking disks 72 have their shafts 73 mounted in suitable bearings in the carriages 63.

30 The web as it passes through the rolls 34, 35, is guided downwardly to the first reel 56 between a fixed guide 74 and an extensible guide 75, one end of which extensible guide 35 is attached to a spring roll 76 and the other end of which extensible guide is attached to the carriages 63.

35 The shaft 61 of the second reel 55 is slideable in the curved slots 77 in the frame. 40 The shafts 60 and 61 are connected through rocking arms 78 and the shafts 61 and 62 are connected through the rocking arms 79. It is understood that there is a slot 77 in each of the side frames and that there are 45 two sets of arms 78, 79.

The grippers on the first reel 56 are denoted by 80, the grippers on the second reel 55 by 81, and the grippers on the third reel 54 by 82. The grippers 80 on the first reel 56 are opened to receive the advance edge 70 of the sheet and closed upon the same by suitable tumbler cam mechanism 83. These grippers are opened to transfer the advance edge of the sheet to the grippers 81, of the second reel by a cam 84 on one of the arms 75 79. The grippers 81 on the second reel are opened to receive the advance edge of the sheet from the grippers 80 of the first reel and are open to transfer the advance edge 80 of the sheet to the grippers 82 of the third reel irrespective of the position of the reels 55 and 56 with respect to each other and the reel 54, by means of a divided cam 85, 86, one part secured to the arm 79 and the other part to the arm 78.

85 The grippers 82 of the third reel are opened to receive the advance edge of the sheet from the grippers 81 of the second reel by a cam 87 on one of the arms 78 and these grippers 82 are opened to transfer the advance edge of the sheet to one of the grippers of the impression cylinder by means of a cam 88 carried by the side frame.

90 The shaft 33 which carries the intermediate gears 31, 32, is movable in the curved elongated slots 89 concentric with the shaft 18 for permitting the introduction of gears 32 of different diameters according to the speed which it is desired to drive the web 19.

95 In operation, presupposing the parts to be in the position shown in Figs. 1, 2 and 5, for the cutting of a long sheet from the web and the feeding of the same to the printing mechanism: The proper size of gear 32 is introduced for driving the web feed rolls 20, 21, 22, 23, at the proper surface speed to feed the web 19 at the desired speed for causing the cutters 10, 11, to sever a sheet of the desired length. The elliptical 100 gears 16, 17, are then adjusted rotatively with respect to the shaft of the rotary cutter 11 so that the blades 12, 13, will cut the sheets when traveling at the surface speed of the web. The feed rolls 34, 35, will be 105 driven at the desired speed from the shaft 40 of the feed roll 23. The first reel 56 is adjusted so as to take the advance edge of the sheet at about the time when the sheet is severed from the web.

110 The tucking disks 72 serve to insure the introduction of the advance edge of the sheet into the grippers 80 of the first reel. This reel then transfers the sheet to the second reel and the second reel transfers the 115 sheet to the first reel. This third reel transfers the sheet to the impression cylinder.

120 When a shorter sheet is to be cut and fed, a gear 32 of the proper size is introduced 125 130

for driving the feed rolls 20, 21, 22, 23, at the desired speed for feeding the web to the cutters at the slower speed required for the shorter sheet. The elliptical gears 16, 5 17, are then rotatively adjusted with respect to the shaft of the cutter 11 so that the blades 12 and 13 will cut the shorter sheet from the web while traveling at the surface speed of the web.

10 The feed rolls 34, 35, will be driven at the surface speed of the web from the shaft 40 of the feed roll 23. The first reel 56 is adjusted upwardly by the turning of the screw shafts 64 until the reel is adjusted 15 in the proper position for receiving the advance edge of the shorter sheet at about the time the sheet is severed from the web. This vertical adjustment of the first reel 56 will move the second reel 55 around the 20 third reel 54 without disturbing the co-active relationship of the reels with respect to each other and with respect to the impression cylinder.

As the surface speed of the reels is not 25 changed for the different lengths of sheets, it is found desirable to use a tumbler cam mechanism for opening and closing the grippers 80 of the first reel and it is also found desirable to provide the roll 35 with 30 a slip clutch connection so that when the grippers 80 close upon the advance edge of the shorter sheet the tail end of the sheet may be pulled through the rolls 34, 35, at a surface speed greater than the surface 35 speed of the said rolls. If so desired, these feed rolls 34, 35, may be put out of operation for the handling of the longer sheets, as the grippers on the first reel may be adjusted to receive the leading edge of the 40 sheet just before the sheet is severed from the web.

It will be seen from the above description 45 that a machine is provided which may cut sheets of different lengths from a continuously running web and feed the same to the printing mechanism, the parts being very readily adjustable to suit the different lengths of sheets being cut and fed.

It is evident that changes might be resorted to in the form, construction and arrangement of the several parts without departing from the spirit and scope of my invention; hence I do not wish to limit myself strictly to the structure herein set forth, but

What I claim is:—

1. In a machine for cutting sheets and feeding them to a printing mechanism, a web, means for cutting sheets of different lengths therefrom and means for feeding the different length sheets to the printing mechanism including a plurality of coacting rotary carriers and means for bodily adjusting said carriers without changing 60 their surface speed or coactive relationship.

2. In a machine for cutting sheets and feeding them to a printing mechanism, a web, means driven at a varying speed for cutting sheets of different lengths therefrom at the surface speed of the web and 70 means for feeding the different length sheets to the printing mechanism including a plurality of coacting rotary carriers, and means for bodily adjusting said carriers without changing their surface speed or coactive relationship. 75

3. In a machine for cutting sheets and feeding them to a printing mechanism, a web, means for cutting sheets of different lengths therefrom and means for feeding 80 the different length sheets to the printing mechanism including a plurality of coacting rotary carriers, one of said carriers being adjustable toward and away from the sheet cutting means. 85

4. In a machine for cutting sheets and feeding them to a printing mechanism, a web, means driven at a varying speed for cutting sheets of different lengths therefrom and means for feeding the different length 90 sheets to the printing mechanism including a plurality of coacting rotary carriers, one of said carriers being adjustable toward and away from the sheet cutting means.

5. In a machine for cutting sheets and feeding them to a printing mechanism, a web, means for cutting sheets of different lengths therefrom and means for feeding the different length sheets to the printing mechanism including three coacting rotary 100 carriers, and means for bodily adjusting two of said carriers without changing their surface speed or coactive relationship. 95

6. In a machine for cutting sheets and feeding them to a printing mechanism, a web, means driven at a varying speed for cutting sheets of different lengths therefrom at the surface speed of the web and means for feeding the different length sheets to the printing mechanism including three 110 coacting rotary carriers, and means for bodily adjusting two of said carriers rotatively without changing their surface speed or coactive relationship. 105

7. In a machine for cutting sheets and feeding them to a printing mechanism, a web, means for cutting sheets of different lengths therefrom and means for feeding the different length sheets to the printing mechanism including three coacting rotary 120 carriers, the first being adjustable toward and away from the sheet cutting means and the second being adjustable about the third. 115

8. In a machine for cutting sheets and feeding them to a printing mechanism, a web, means driven at a varying speed for cutting sheets of different lengths therefrom, and means for feeding the different length sheets to the printing mechanism including three coacting rotary carriers, the 125 130

first being adjustable toward and away from the sheet cutting means and the second being adjustable about the third.

9. In a machine for cutting sheets and

5 feeding them to a printing mechanism, a web, means for feeding it at different uniform speeds, means driven at a varying speed for cutting sheets of different lengths therefrom at the surface speed of the web
10 and means for feeding the sheets to the printing mechanism.

10. In a machine for cutting sheets and feeding them to a printing mechanism, a web, means for feeding it at different speeds, 15 means driven at a varying speed for cutting sheets of different lengths therefrom at the surface speed of the web and means for feeding the different length sheets to the printing mechanism including a plurality of adjustable coacting rotary carriers.

11. In a machine for cutting sheets and feeding them to a printing mechanism, a web, means for feeding it at different speeds, means driven at a varying speed for 25 cutting sheets of different lengths therefrom at the surface speed of the web and means for feeding the different length sheets to the printing mechanism including a plurality of coacting rotary carriers, one 30 of said carriers being adjustable toward and away from the sheet cutting means.

12. In a machine for cutting sheets and feeding them to a printing mechanism, a web, means for feeding it at different 35 speeds, means driven at a varying speed for cutting sheets of different lengths therefrom at the surface speed of the web and means for feeding the different length sheets to the printing mechanism including three co- 40 acting rotary carriers, two of said carriers being adjustable.

13. In a machine for cutting sheets and feeding them to a printing mechanism, a web, means for feeding it at different 45 speeds, means driven at a varying speed for cutting sheets of different lengths therefrom at the surface speed of the web and means for feeding the different length sheets to the printing mechanism includ-

ing three coacting rotary carriers, the first 50 being adjustable toward and away from the sheet cutting means and the second being adjustable about the third.

14. In a machine for cutting sheets and feeding them to a printing mechanism, a 55 web, means for feeding it at different speeds, means driven at a varying speed for cutting sheets of different lengths therefrom at the surface speed of the web and means for feeding the different length sheets to 60 the printing mechanism including three coacting rotary carriers and a common means for adjusting the position of the first carrier with respect to the sheet cutting means and the position of the second carrier with 65 respect to the first and third carriers.

15. In a machine for cutting sheets and feeding them to a printing mechanism, a web, means for feeding it at different 70 speeds, means driven at a varying speed for cutting sheets of different lengths therefrom at the surface speed of the web and means for feeding the different length sheets to the printing mechanism including three coacting rotary carriers and a common 75 means for adjusting the first carrier in a right line toward and away from the cutters and the second carrier in a curved line concentric with the axis of the third carrier.

16. A web, means for feeding it at different uniform speeds and means driven at a varying speed for cutting sheets of different lengths therefrom at the surface speed of the web. 80

17. A pair of coacting rotary cutters, a 85 web, means for feeding it at different uniform speeds to the cutters and means for rotating the cutters at a varying speed to cause the cutters to operate on the web while traveling at the surface speed of the web. 90

In testimony, that I claim the foregoing as my invention, I have signed my name in presence of two witnesses, this ninth day of December, 1913.

HOWARD M. BARBER.
